UNITED STATES PATENT OFFICE.

JOHN L. FERGUSON, OF JOLIET, ILLINOIS.

DEVICE FOR OPERATING ON CONTAINERS.

1,423,098.

Specification of Letters Patent.

Patented July 18, 1922.

Application filed January 25, 1917, Serial No. 144,551. Renewed March 1, 1921. Serial No. 448,744.

To all whom it may concern:

Be it known that I, JOHN L. FERGUSON, a citizen of the United States, residing at Joliet, in the county of Will and State of Illinois, have invented new and useful Improvements in Devices for Operating on Containers, of which the following is a full, clear, concise, and exact description, reference being had to the accompanying drawing, forming a part of this specification.

My invention relates to a device for operating on containers and more specifically to a machine for placing the flanged caps in closing position with respect to containers.

Among the objects of my invention is to provide an improved machine of the character described which will insure the proper placing of the caps without injury to the flanges.

Further objects will appear from the detailed description to follow taken in connection with the appended claims.

In the drawings, in which two embodiments of my invention are shown—

Fig. 1 is a side elevation of a container-capping machine embodying my invention;

Fig. 2 is a plan view thereof;

Fig. 3 is a section on the line 3—3 of Fig. 2;

Fig. 4 is a section on the line 4—4 of Fig. 1;

Fig. 5 is a section on the line 5—5 of Fig. 1;

Fig. 6 is a section on the line 6—6 of Fig. 2;

Fig. 7 is a detailed plan view of the mechanism for operating on the caps;

Fig. 8 is a section on the line 8—8 of Fig. 7;

Fig. 9 is a detail side elevation of the mechanism for placing the containers on the holders;

Fig. 10 is a detail plan view of the parts shown in Fig. 9;

Fig. 11 is a detail vertical sectional view on the line 11—11 of Fig. 1, showing the blow-off device;

Fig. 12 is a detail perspective view of a chain guide;

Fig. 13 is a side elevation showing the spring fingers and chain;

Fig. 14 is a section on the line 14—14 of Fig. 13;

Fig. 15 is a detail side elevation showing a position the cap and associated parts assume in their travels;

Fig. 16 is a plan view of the parts shown in Fig. 15;

Fig. 17 is a detail side elevation showing a further advanced position of the cap and associated parts;

Fig. 18 is a section on the line 18—18 of Fig. 17;

Figs. 19, 20, and 21 are detail sectional elevations showing progressively the positions assumed by the cap and spring fingers;

Fig. 22 is an axial cross sectional view showing another form of my invention;

Fig. 23 is a bottom plan view of the device shown in Fig. 22;

Fig. 24 is a section similar to Fig. 22 showing the arms expanded; and

Fig. 25 is a section on the line 25—25 of Fig. 22.

Referring to the drawings in detail, and first to Figs. 1 to 21, inclusive, the machine shown comprises a supporting frame 30, mechanism 31 for supplying containers to the container holders 33, conveyor mechanism 34 on which the container holders 80 are mounted, mechanism 35 for supplying caps 36 adjacent the containers as they travel, mechanism 37 for receiving the caps from the supply mechanism and placing them in proper closing position on the containers as they travel, pneumatic mechanism 37^a for removing the containers, closed at one end, from the holders 33 and placing them open end up on the conveyor 38, a filling mechanism 39 for filling the containers 85 as they are positioned therebeneath on the conveyor 38, mechanism 40 for transferring the filled containers from the conveyor 38 one at a time onto the chairs, supports, or holders 41, and conveying mechanism 42 on 90 which the supports 41 are mounted for carrying the filled containers beneath the capping mechanism.

The conveyor mechanism 34 for the empty containers and the conveyor mechanism 42 100 for the filled containers are substantially the same, and each comprises an endless chain 43 provided at intervals with brackets 44 to which the holders 33 and 41 are secured, and a pair of sprocket wheels 45 and 46 over 105 which the chain 43 runs. Each chain 43 is driven from the sprocket 45 keyed on the shaft 47 mounted in a bearing 48 supported by the frame 30. Each shaft 47 is driven from the driving belt 49 through a pulley 50 110 over which the belt runs, a shaft 51 mounted in a bearing 52 on the main frame and on

which the pulley 50 is keyed, a worm 53 keyed on the shaft 51, and worm wheels 54 meshing with the worm 53 and keyed on the shaft 47. The arms of the chain 43 between 5 the sprockets 45 and 46 travel in channeled tracks 55 and 56, which off-set these runs on both sides from a plane through the axes of the sprockets for a purpose to be hereinafter described.

- 10 The tracks 55 for both of the chains 43 are so located that the holders 33 and 41 secured to those parts of the chains engaging the tracks travel in substantially the same path beneath the cap supplying mechanism 15 35, the holders 33 and supports 41 being so spaced and the chains being so timed that the holders and supports will be evenly and alternately spaced as they travel beneath the cap supplying mechanism. The travel of 20 the holders and supports is as indicated by the arrow A in Fig. 2. The sprockets 46 are mounted on stub shafts 56^a secured on the frame 30 of the machine (Fig. 3). Each container holder 33 comprises a cylindrical 25 portion 57 over which the cylindrical container fits, an annular flange or shoulder 58 against which the lower edge of the carton rests, a base portion 59 secured to the bracket 44 and a nozzle or passage 60 for directing a 30 blast of air from a nozzle 60^a (Fig. 11) to blow the container from the holder. The base portion 59 of the holders 33 and the base portion 60^b of the supports 41 are supported in their travel by spaced tracks 61 35 and 62 in turn supported on brackets 63 and 64, respectively, secured to the frame 30 and tracks 55 and 56, respectively. The holder 33 is recessed at 65 for co-operation with the mechanism for controlling the supply of 40 containers and caps, as hereinafter described. The mechanism 31 for supplying the containers to the holder 33 comprises a tubular chute 66 supplied, in any suitable manner, with containers placed end to end, mechanism 43 controlled by the conveyor mechanism 43 for retaining the containers in the chutes 66 until a holder 33 is in proper position beneath the chute to receive a container and emergency mechanism 68 for preventing 45 50 an additional container from being supplied from the chute to a holder already supplied with a container (a condition which might exist in case a container had failed to receive a cap, or the blast delivered from the nozzle 55 60^b should fail to remove the capped container from a holder), the mechanism 68 being controlled from the container remaining on the holder.

The chute 66 is inclined and its lower end 60 is so located that a container held in the lower end of the chute will have its lower inside edge engaged by the upper end of a holder 33 in its travel, and will be removed from the chute by said holder and dropped 65 down over the holder until its lower edge

engages the flange 58, the chute 66 being cut away at 69 to facilitate this operation.

A finger 70 is secured to the lower end of the chute having a portion 71 located in the path of movement of the containers in the 70 chute to properly position the lowermost container with respect to the holder 33.

The mechanism 67 for retaining the containers in the chute until a holder 33 is in proper position comprises a vertical rock 75 shaft 72 mounted in a bearing 73, a retaining arm 74 secured to the rock shaft having a portion 75 movable through an opening 76 in the chute 66 into and out of the path of movement of the containers in the chute, a 80 retaining arm 77 also secured to the rock shaft and having a portion 78 movable through the opening 79 in the chute into and out of engagement with the sides of the containers in the chute, an operating arm 80 85 having a portion located in the path of movement of the holders 33 and a spring 81 secured at one end to the arm 80 and at the other to a screw 82 for normally holding the portion 75 of the arm 74 in the path of the 90 containers in the chute.

The emergency mechanism 68 comprises a vertical rock shaft 83 mounted in a bearing 84, a retaining arm 85 secured to the shaft 83 and having a portion 86 movable 95 through an opening 87 in the chute into and out of the path of movement of the container, an operating arm 88 also secured to the shaft 83 and having a portion 89 located in the path of the containers on the holders 100 33 but so that the holders 33 themselves will clear it, down to the recesses 65 as shown in Fig. 5. The portion 89 of the operating arm is so located that if a container is accidentally left on a holder 33 as it approaches 105 the chute 66 this container will engage the portion 89 to cause the portion 86 of the retaining arm to enter the opening 87 in the chute, before the holder 33 releases the operating arm 80 permitting the spring 81 to 110 rock the shaft 72 to withdraw the portion 78 of the retaining arm 77 from engagement with a container in the chute. Also the portion 89 of the operating arm is of such extent (see Figs. 2 and 4) that when engaged 115 by a container accidentally left on the holder the portion 86 of the retaining arm will be held beneath the container in the chute until the holder on which the container has been left has operated and released the arm 80. 120

A spring 89^a is provided for returning the operating arm 88, and suitable stops 89^b and 89^c are provided to limit the movement of the operating arms 80 and 88, respectively, due to the springs 81 and 89^a. 125

The pneumatic mechanism 37^a for removing the cartons from the holders 33 after the caps have been placed on one end of the containers and placing them open end up on the conveyor 38 comprises an arched tube 90 130

having one open end 91 (Figs. 1 and 11) located directly above the nozzle 60^a and so that the containers capped at one end, pass beneath said open end 91 and the other open end 92 positioned above the conveyor 38 (Fig. 6) far enough above the conveyor to permit a container to clear the end of the tube when it rests in the conveyor. Any suitable mechanism can be employed for causing a blast of air to be delivered through the nozzle 60^a just as the nozzle or passage 60 registers therewith, to blow the capped container from the holder up through the tube 90 to cause it to be deposited open end 15 up on the conveyor 38.

The conveyor 38 comprises an endless belt 93 extending over pulleys 94 and 95 the upper run of the belt traveling over a support 96 supported on brackets 97 and 98 secured to the frame 30. The conveyor 38 is driven from the shaft 51 through a worm 99, a shaft 101 (mounted in bearing brackets 102 secured to the frame 30) on which the wheel 100 is secured, a sprocket 103 secured 25 on the shaft 101, a chain 104 extending over the sprocket 103, a sprocket 105 over which the chain 104 extends, and a shaft 106 to which both the pulley 95 and sprocket 105 are secured. Direction of the travel of the 30 belt is as indicated by the arrow B, Fig. 6.

The mechanism for filling the containers on the conveyor 38 may be of any suitable type and as shown comprises three discharge spouts arranged so that three of the containers can be simultaneously filled, the containers being properly positioned beneath the discharge spouts and held there long enough to be filled by any suitable mechanism (not shown).

The mechanism 40 for transferring the filled containers from the conveyor 38 onto the supports 41 comprises a revolute member 107 having a surface portion 108 engageable by the containers in their travel on the belt 93 which holds the containers against forward movement during a part of the revolution of the member 107, said member, however, being recessed as indicated at 109 to permit the containers to move past it during another part of its revolution. This revolute member is so timed with the supports or chairs 41, that it will allow the container to pass just in time to be deflected by the fixed guide 110 onto one of the supports or chairs 41 as it travels along. The supports 41 are provided with curved arms 111 secured to supports 112 mounted in the base 60^b for holding and positioning the containers on the supports, and a fixed curved 45 guide 113 opposite the deflecting guide 110 serves to prevent the containers from tipping over as they are deflected onto the supports 41. Fixed guides 114 may be provided on opposite sides of the belt 93 to prevent 55 the containers from slipping off the belt.

The revolute member 107 is driven from the shaft 101 through the sprocket 115 secured to the shaft 101, the chain 116 extending over the sprocket 115, the sprocket 117 over which the chain 116 extends, and a shaft 118 (mounted in suitable bearings 119 in the bracket 98) to which both the sprocket 117 and the revolute member 107 are secured. The mechanism 35 for supplying the caps adjacent the travel of the containers 75 comprises an inclined chute 120 in which the flanged caps are placed in series edge to edge, retaining mechanism 121 controlled by the containers in their travel for preventing caps from being supplied to holders not supplied with containers, and feed mechanism 122 for assisting in removing the caps from the chute and moving them into the path of the mechanism 37 which places them in proper closing position on the containers. 80

The retaining mechanism 121 comprises a rock shaft 123 mounted in a suitably supported bearing 124, a retaining arm 125 secured to the rock shaft 123 and having a portion 126 movable through an opening 127 90 in the chute 120, into and out of the path of the caps in the chute, and an operating arm 128 also secured to the shaft 123 and having a portion located in position to be engaged and operated by the containers on 95 the holders 33 (Figs. 4 and 5) but so that if one of the holders should not be provided with a container the holder itself will clear the operating arm, due to the recesses 65 as shown in Fig. 5. A spring 128^a serves to 100 normally hold the operating arm 128 in the path of the containers. The arms 125 and 128 are so positioned that when a container engages and operates the arm 128 the portion 126 in the arm 125 will be withdrawn 105 from the path of the caps. The feed mechanism which assists in removing the caps from the chute 120 comprises a friction feed wheel or roller 122 (having a portion extending through an opening 130 in the chute 110 120 in position to engage the caps 36 as they are released from the retaining arm 125) secured to a shaft 131 mounted in bearings 132 in a swinging or floating bracket 133 pivoted on the shaft 134 mounted in bearings on the bracket 135. For preventing the roller 122 from dropping too low an adjustable stop is provided on which the floating bracket 133 may rest comprising a screw 136 threaded through a boss 137 on 120 the bracket 135 and engaging the other side of the bracket 133 to prevent it from dropping too low. The feed wheel 122 is driven from the shaft 101 through the sprocket 138 secured on the shaft 101, a chain 139 extending over the sprocket 138, a sprocket 140 over which the chain 139 extends, the shaft 134 mounted in the bracket 135, the sprocket 141 also secured to the shaft 134, a chain 142 extending over the sprocket 141, a sprocket 130

143 over which the chain 142 extends, and the shaft 131 to which both the sprocket 143 and the feed wheel 122 are secured.

The mechanism 37 for receiving the caps from the supply mechanism 35 (just described) and placing them on the containers comprises a pair of chains 144 and 145 constructed to travel along with the conveyors 34-43 but inclined somewhat with respect thereto (Figs. 1, 3 and 8) and a series of sets of yielding spring guide fingers 146 carried by the chains 144-145, which fingers in their travel receive the caps from the chute 120 as they are fed therefrom by the feed wheel 122 (Fig. 15), and surround and travel along with the cartons on the conveyors 34-43 and downwardly with respect thereto due to the inclination of the chains 144-145 (Figs. 17, 18, 19, 20, and 21), to slip the flanges 147 of the caps 36 down over the tubular cartons 32. As the friction between the spring fingers 146 and the flanges 147 might not always be sufficient to prevent the caps from tilting or slipping from the fingers additional means 148 may be provided to assist in forcing the caps in place, comprising a plurality of rollers 149 located in bearings on a suitably supported bracket 150. These rollers 149 are constructed and positioned so that the lower faces of those rollers farthest from the chute 120 are the lowest so that they tend to force the cap downwardly gradually over the container. The yielding fingers 146 are arranged in a series of semi-cylindrical sets on the chains 144-145, these chains being so timed that the sets on one chain come opposite the sets on the other chain on the adjacent runs of the two chains 40 to form together a circular arrangement of the spring fingers for extending within the flange of the cap and surrounding the container. These semi-cylindrical sets of fingers are formed by mounting the fingers on a pair of arcuate arms 151 (Fig. 14) secured to extensions 152 on the links 153 of the chains 144-145. Each of the chains 144-145 runs over two sprockets 154-155, each sprocket 154 being secured to an inclined shaft 156 rotatable in a suitably supported bearing 157 and connected to the shaft 47 from which it is driven by means of a universal coupling 158 which permits the inclination of the shaft 156. Each sprocket 155 is mounted on a pin 159 in a suitable bracket 160. Each of the chains 144-145 is provided with inner and outer tracks 161 and 162 respectively between the sprockets 154-155 the inner tracks 161 off-setting the chains with respect to a plane through the axes of the sprockets 154-155 and the outer tracks in-setting the chains with respect to said plane. As previously described the guides 55 and 56 off-set both sides of the chains 43 with respect to the planes through

the axes of the gears 44-45. On each side of the machine, the axes of the sprockets 45, 46, 154 and 155 all lie in a common plane.

With this arrangement of the tracks 55-56 and the tracks 161-162 it follows that the yielding fingers 146 travel close to the holders 33 and chairs 41 on the inside runs of the chains 43, 144, and 145 and travel at a distance from the holders and chairs on the outside runs of the chains. This enables the containers to be readily placed on the holders on the outside runs of the chain 43 without interference from the spring fingers. Also the tracks 55 and 161 are so arranged that when the chains 43, 144 and 145 leave these tracks the chains 43 will diverge gradually and the chains 144 and 145 will also diverge gradually. From this it follows that the yielding fingers 146 on the chain 145 will gradually draw away from the containers on the holders 33 and the yielding fingers on the chain 144 will gradually draw away from the containers on the chairs 41. As the change in direction of the chains at the points where they leave the tracks is slight there will be no considerable relative angular movement between the spring finger supporting arms 151 and the holders 33 and chairs 41 at these points, and consequently little tendency for the spring fingers or the spring arms to dig into the containers.

In order to prevent the chains 144-145 from slipping out of the tracks 162 the latter are provided with retaining flanges 163 which resist the tendency of the chains to pull out of the tracks. For removing the filled and capped containers from the chairs 41 the curved deflectors 164 may be provided located in the path of these containers for deflecting them onto any suitable support 165.

The operation of this machine is as follows. Power is applied through the belt 49 to drive the conveyor 34 for carrying the empty containers under the capping mechanism, the conveyor 38 for carrying the containers under the filling mechanism 39, transfer mechanism 40 for transferring the filled containers onto the chairs 41, the conveyor 43 for carrying the filled containers under the capping mechanism, the feed wheel 122 for feeding the caps from the chute 120 and the chains 144-145 carrying the yielding fingers 146 through the transmission mechanism previously described. As an empty holder 33 approaches the container chute 66 it engages the arm 80 of the container retaining mechanism 67 and moves it against the tension of the spring 81 to cause the portion 78 of the arm 77 to move through the opening 79 to engage the side of a container in the tube and the portion 75 of the arm 74 to move out of the path of the containers in the chute to permit the lowermost container to drop down until its lower edge engages

the portion 71 of the retaining finger 70, the arm 77 meanwhile holding the succeeding container against movement. Then as the holder 33 advances its upper portion engages the inside lower edge of the lowermost container and moves it along as indicated in dotted lines (Fig. 9) until it drops down over the holder and its lower edge engages the shoulder 58. As the holder with the container in place approaches the capping mechanism the container engages the operating arm 128 of the cap retaining mechanism 121 and moves it against the tension of the spring 128^a to move the portion 126 of the retaining arm 125 out of the path of the caps in the chute. The lowermost cap then moves down in the chute and is engaged by the feed roll 129 which feeds it downwardly until the flange of the cap is in position to be engaged by the spring fingers 146 (Fig. 15). As the container holder continues to advance the spring fingers 146 which surround the container and extend above it receive the cap from the chute, the flange of the cap surrounding the upper ends of the fingers.

Due to the inclination of the chains 144-145 with respect to the conveyors 34-42 the spring fingers 146 will gradually move downward along the sides of the container as the container advances carrying the cap along with them until the top of the cap engages the upper edge of the container, (Figs. 18, 19 and 20). As the container continues to advance the spring fingers will be withdrawn from between the flange of the cap and the sides of the carton leaving the cap in proper position on the container. The rollers 149 assist in forcing the cap in position. As the container with the cap on its upper end continues to advance it comes into position beneath the open end 91 of the tube 90 and above the nozzle 60^a which at the proper time delivers a blast of air to the passage 60 to blow the capped container into and through the tube 90 from whence it is deposited open end up on the belt 93. The belt 93 carries the container closed at its lower end beneath the filling machine 39 where it is filled. The container is then carried by the belt 93 until the side of the container engages the surface 108 of the transfer mechanism 40 where it is held until the member 107 has revolved to a position in which the recess 109 comes opposite the container, permitting the belt to carry the container forward along the guide 109 which deflects the container from the belt onto one of the chairs 41 which is properly timed with respect to the revoluble member 107. The filled container is then carried on the chair 41 beneath the capping mechanism when the cap is placed on its upper end in the manner just described in connection with the empty container. The filled and

capped container is then removed from the chair 41 by the deflector 164 onto the support 165. In case the holder 33 or chair 41 as it comes beneath the capping mechanism is not supplied with a container no cap will be supplied this holder as the operating arm 128 of the retaining mechanism 121 is so located that it will not be actuated by the empty holder or chair. In case one of the holders 33 should be already supplied with a container as it approaches the container supply mechanism 31 no additional container will be supplied to this holder as the container already supplied to the holder will engage the operating arm 88 of the emergency mechanism 68 to move the portion 86 of the retaining arm 85 into the path of the containers in the chute 66 and will continue in engagement with this arm 88 until its holder has operated and released the operating arm 80.

The form of my invention shown in Figs. 22 to 25 inclusive may be operated by a power driven machine or may be used as a hand device for placing caps on containers. The device shown comprises a guiding and supporting member 166 to which are pivoted in circular arrangement a plurality of arms 167, and an actuating guiding and cap engaging member 168 movable toward and from the member 166 for moving the fingers 167 from the position shown in Fig. 22 to the position shown in Fig. 24 and vice versa. The guiding and supporting member 166 comprises a circular plate 169 having its outer edge cut and bent to form radially extending fingers 170 each having an opening through which extends a circular wire 171 which also extends through openings formed in the arms 167 to form a pivotal support for the latter, and a guiding or spacing plate 172 for the ends of the fingers 167 having radial slots 173 in which the ends of the fingers work. These plates 169-172 may be fixedly secured together in any suitable manner as by soldering. The actuating and guiding member 168 comprises a circular plate 174 having its outer edge cut and bent to form radially extending fingers 175, each finger having an opening through which a circular wire 176 extends which wire also extends through angular slots 177 in the arms 167, and a guiding or spacing plate 178 having radial slots 179 in which the arms 167 work. These plates 178-174 are fixedly secured together in any suitable manner as by soldering. The supporting member 166 is fixedly secured to a rod 180 by means of a pin 181 extending through the rod 180 and through the sleeve 182 to which the plate 172 is secured. The actuating member 168 is fixedly secured to a sleeve 183 (slidable on the rod 180) in any suitable manner as by riveting or soldering the plate 174 to the flange 184 on the sleeve 180.

183. The arms 167 are provided with yielding flexible bent fingers 185 the ends of which are to be positioned inside of the flange of the cap and which slip down over 5 the container. The actuating member 168 in addition to actuating the arms 167 also aids in pressing the cap in place on the container by engaging the top of the cap. Each slot 177 comprises a portion 186 along which the 10 wire 176 slides to move the arms 167 from the expanded to the contracted position and a portion 187 extending at such an angle that movement of the wire 176 in this part of the slot does not materially change the 15 position of the arm 167, this latter part of the slot being provided to permit proper withdrawal of the fingers 185 from between the flange of the cap 188 and the sides of the container 189 after the cap has been 20 properly placed on the container. The pin 181 engages slots 190 in the sleeve 183 which construction prevents relative rotation between the rod 180 and the sleeve 183.

The operation of this form of my invention 25 is as follows: Assuming that the device is to be used as a manually operated machine the sleeve 183 is grasped in one hand and the rod 180 in the other and relative movement of the sleeve and rod is effected 30 to bring the arms 167 to expanded position (Fig. 24). The cap 188 is then placed in position as indicated in Fig. 24, the device being inverted if desired to facilitate this positioning, and relative movement between 35 the rod 180 and sleeve 183 is effected to bring the arms 167 to contracted position and the cap to the position indicated in dotted lines in Fig. 22, with its flange surrounding the ends of the fingers 185. The device carrying 40 the cap is then brought in position over the open end of a container with the fingers 185 surrounding the open end of the container. The device is then moved downward, the fingers 185 slipping down over the end 45 of the container and carrying the cap 188 into position. The member 168 assists in pressing the cap into place by engaging the top of the cap and forcing it down on the container. After the cap is partly in place 50 on container the fingers 185 are withdrawn from between the flange of the cap and the sides of the container by downward movement of the rod 180 which moves the fingers 185 downward without causing them to expand as long as the wire 176 engages the 55 portion 187 of the slot 177. By the time the wire 176 engages the portion 186 of the slot 177 the fingers 185 will have been completely withdrawn from between the flange 60 of the cap and the sides of the container. Further downward movement of the rod 180 will cause the arms 167 to expand to the position shown in Fig. 24 permitting the 65 whole device to be removed from the capped container leaving the cap in position.

While I have described but two embodiments of my invention it is obvious that many modifications therein may occur to those skilled in the art and I desire, therefore, that the same be limited only by the 70 showing of the prior art and by the scope of the appended claims, it being apparent that many changes in the hereinbefore mentioned apparatus may be made and the apparatus still be within the spirit of said 75 claims.

Having thus described my invention what I claim as new and desire to secure by Letters Patent is:—

1. A machine for placing peripherally flanged closures in closing position with respect to the openings of containers comprising a conveyor for the containers a guide member for traveling along with the containers and means whereby said guide member is positioned between the inner surfaces of the flanges of the closures and adjacent portions of the containers to guide the closures and the containers in their relative movement. 90

2. A machine for placing peripherally flanged closures in closing position with respect to the openings of containers comprising a conveyor for the containers, a plurality of sets of yielding guide fingers for traveling along with the containers and means whereby said guide fingers are positioned between the flanges of the closures and adjacent portions of the containers, for controlling the relative movement between the closures and the containers. 95

3. A machine for placing peripherally flanged caps in closing position with their flanges surrounding the tubular portions of containers comprising a conveyor for the containers, a set of yielding guide fingers traveling along with the containers on the conveyor, and means whereby said fingers are positioned between the flanges of said caps and the adjacent tubular portions of the containers, for controlling the relative movement between the caps and the containers. 105

4. A machine for placing peripherally flanged caps in closing position with their flanges associated with the tubular portions of containers comprising a conveyor for the containers, a set of yielding guide fingers traveling along with the containers on the conveyor, means whereby said fingers are positioned between the flange of the cap and the adjacent tubular portion, for controlling the relative movement between the cap and the container, and means for supplying caps adjacent said containers. 115

5. A machine for placing peripherally flanged caps in closing position with their flanges associated with the tubular portions of containers comprising a conveyor for the containers, a set of yielding guide fingers 120

travelling along with the containers on the conveyor to be positioned between the flanges of the caps and said tubular portions, and means for withdrawing said fingers from 5 between said flanges and said tubular portions.

6. A machine for placing peripherally flanged caps in closing position with their flanges associated with the tubular portions 10 of containers comprising a conveyor for the containers, and a set of yielding guide fingers traveling along with the containers on the conveyor, and means for causing said guide fingers to be positioned between the flanges 15 of the caps and said tubular portions and to move from a position in which they extend beyond the ends of said tubular portions, to a position in which they do not extend beyond the ends of said tubular 20 portions.

7. A machine for placing peripherally flanged caps in closing position with their flanges associated with the tubular portions 25 of containers comprising a conveyor for the containers, a set of yielding guide fingers traveling along with the containers on the conveyor, and means whereby said fingers are positioned between the flanges of the caps and said tubular portions, for controlling 30 the relative movement between said caps and said tubular portions, said containers and fingers traveling in substantially straight lines oblique to each other during a portion of said travel.

35 8. A machine for placing peripherally flanged caps in closing position with their flanges surrounding the tubular portions of containers comprising a conveyor for the containers, a set of yielding guide fingers 40 traveling along with the containers on the conveyor, means whereby said fingers are positioned between the flanges of the caps and said tubular portions, and means whereby said containers and fingers travel 45 in substantially straight lines oblique to each other during a portion of said travel and to cause said fingers to move from a position in which they extend beyond the ends of said tubular portions, to a position in 50 which they do not extend beyond said ends.

9. A machine for placing peripherally flanged closures in closing position with respect to the openings of containers comprising an endless chain conveyor for the 55 containers, two sprockets over which the chain runs, a plurality of sets of yielding guide fingers for traveling along with the containers on the conveyor, means whereby said fingers are positioned between the 60 flanges of the closures and portions of the containers adjacent the openings, for controlling the relative movement between said closures and containers, and means for supporting said sets comprising a second endless chain,

10. A machine for placing peripherally flanged closures in closing position with respect to the openings of containers comprising an endless chain conveyor for the containers, two sprockets over which the 70 chain runs, a plurality of sets of yielding guide fingers for traveling along with the containers on the conveyor, means whereby said fingers are positioned between the flanges of the closures and portions of the containers adjacent the openings, for controlling the relative movement between said closures and containers, means for supporting said sets comprising a second endless chain, and two sprockets over 75 which said second endless chain runs the axes of all of said sprockets lying substantially in a common plane.

11. A machine for placing peripherally flanged closures in closing position with respect to the openings of containers comprising an endless chain conveyor for the containers, two sprockets over which the chain runs, a plurality of sets of yielding guide fingers for traveling along with the 85 containers on the conveyor, means whereby said guide fingers are positioned between the flanges of the closures and portions of the containers adjacent the openings, for controlling the relative movement between 90 said closures and containers, means for supporting said sets comprising a second endless chain, two sprockets over which said second endless chain runs, the axes of all 95 said sprockets lying substantially in a common plane, and guides for portions of said chains between said sprockets.

12. A machine for placing peripherally flanged closures in closing position with respect to the openings of containers comprising an endless chain conveyor for the containers, two sprockets over which the chain runs, a plurality of sets of yielding guide fingers for traveling along with the containers on the conveyor, means whereby said 105 guide fingers are positioned between the flanges of the closures and portions of the containers adjacent the openings, for controlling the relative movement between said closures and containers, means for supporting said sets comprising a second endless chain, two sprockets over which said second endless chain runs, the axes of all 110 said sprockets lying substantially in a common plane, and guides for portions of said chains 115 between said sprockets, said guides being positioned so that the guide fingers travel alongside the containers during a portion of the travel as they move away from said containers.

13. A machine for placing peripherally flanged closures in closing position with respect to the openings of containers comprising an endless conveyor for the containers, driving means for the conveyor, a plurality 120

- 23 of sets of yielding guide fingers for traveling along with the containers on the conveyor to be positioned between the flanges of the closures and portions of the containers adjacent the openings, means for supporting said sets comprising a second endless conveyor and driving means therefor, the axis of all said driving means lying substantially in a common plane, and guides 5 for portions of said conveyors between said driving means, said guides being positioned so that the guide fingers travel alongside the containers during their travel between the driving means on one side of said plane 10 and so that the guide fingers will move away from said containers during the travel between the driving means on the other side of said plane. 15 14. A machine for placing peripherally flanged closures in closing position with respect to the openings of containers comprising an endless chain conveyor for the containers, two sprockets over which the chain runs, a plurality of sets of yielding guide 20 fingers for traveling along with the containers on the conveyor to be positioned between the flanges of the closures and portions of the containers adjacent the openings, means for supporting said sets comprising a second endless chain, and two sprockets over which said second endless chain runs, the axes of all said sprockets lying substantially in a common plane, and guides for portions of said chains 25 between said sprockets, said guides off-setting both chains from planes through the sprocket axis on one side of said plane and off-setting the conveyor chain and insetting the guide finger chain with respect to said 30 plane on the other side of said plane. 35 15. A machine for placing peripherally flanged closures in closing position with respect to the openings of containers comprising an endless chain conveyor for the containers, two sprockets over which the chain runs, a plurality of sets of yielding guide 40 fingers for traveling along the containers on the conveyor to be positioned between the flanges of the closures and portions of the containers adjacent the openings, means for supporting said sets comprising a second endless chain, and two sprockets over which 45 said second endless chain runs, the axes of all said sprockets lying substantially in a common plane, and guides for portions of said chains between said sprockets off-setting the conveyor chain with respect to said plane and insetting the guide finger chain with respect to said plane. 50 55 60 16. A machine for placing peripherally flanged closures in closing position with respect to the openings of containers comprising an endless conveyor for the containers, driving means for the conveyor, a plurality 65 of sets of yielding guide fingers for travel-

ing along the containers on the conveyor to be positioned between the flanges of the closures and portions of the containers adjacent the openings, and means for supporting said sets comprising a second endless conveyor, 70 said conveyors traveling in planes oblique to each other to cause said fingers to be withdrawn from between said flanges and containers.

17. A machine for placing peripherally flanged closures in closing position with respect to the openings of containers comprising a conveyor for the containers guide members for traveling along with the containers, means whereby said guide members are positioned between the inner surfaces of the flanges of the closures and the portions of the containers adjacent the openings, for controlling the relative movement between 80 said closures and containers, and means for supplying the closures adjacent the containers. 85

18. A machine for placing peripherally flanged closures in closing position with respect to the openings of containers comprising a conveyor for the containers guide members for traveling along the containers, means whereby said guide members are positioned between the inner surfaces of the flanges of the closures and the portions of the containers adjacent the openings, for controlling the relative movement between 90 said closures and containers, and means for supplying the closures in the path of movement of said guide member. 95 100

19. A machine for placing peripherally flanged closures in closing position with respect to the openings of containers comprising a conveyor for the containers guide members for traveling along with the containers, means whereby said guide members are positioned between the inner surfaces of the flanges of the closures and the portions of the containers adjacent the openings, for controlling the relative movement between 105 said closures and containers, and means for supplying the closures with their flanges in the path of said guide member. 110

20. A machine for placing peripherally flanged closures in closing position with respect to the openings of containers comprising a conveyor for the containers guide members for traveling along with the containers, means whereby said guide members are positioned between the inner surfaces of the flanges of the closures and the portions of the containers adjacent the openings, for controlling the relative movement between 115 said closures and containers, and means for forcing said closures into closing position. 120 125

21. A machine for placing peripherally flanged closures in closing position with respect to the openings of containers comprising a conveyor for the containers guide members for traveling along with the con- 130

- ainers, means whereby said guide members are positioned between the inner surfaces of the flanges of the closures and the portions of the containers adjacent the openings, for controlling the relative movement between said closures and containers, means for supplying the closures with their flanges in the path of said guide member, and means for forcing said closures into closing position.
- 10 22. A machine for placing peripherally-flanged closures in closing position with respect to the openings of containers comprising a conveyor for the containers guide members for traveling along with the containers, means whereby said guide members are positioned between the inner surfaces of the flanges of the closures and the portions of the containers adjacent the openings, for controlling the relative movement between said closures and containers, and means for forcing said closures into closing position, comprising a plurality of rollers located in the path of said closures.
- 15 23. A machine for placing peripherally-flanged closures in closing position with respect to the openings of containers comprising a conveyor, a plurality of holders on the conveyor over which said containers fit, means for supplying the closures to said containers, retaining means for preventing closures from being supplied to empty holders, and means for controlling said retaining means located in the path of said containers, said holders being recessed to clear said controlling means.
- 20 24. A machine for operating on containers comprising a conveyor, a plurality of holders carried by said conveyor for said containers, means for supplying containers to said holders, and retaining means for preventing additional containers from being supplied to those holders already supplied with containers, controlled by the containers on the holders.
- 25 25. A machine for operating on containers comprising a conveyor, a plurality of holders carried by said conveyor for said containers, means for supplying containers to said holders, and retaining means for preventing additional containers from being supplied to those holders already supplied with containers, and means for controlling said retaining means located in the path of said containers.
- 30 26. A machine for operating on containers comprising a conveyor, a plurality of holders carried by said conveyor for said containers, a guide chute for supplying containers to said holders, retaining means for holding said containers in said chute, means governed by the presence of a holder for controlling said retaining means, a second retaining means for preventing containers from being supplied to those holders already supplied with containers, and means
- for controlling said second retaining means located in the path of said containers on said holders.
- 35 27. A device for placing a peripherally-flanged closure in closing position with respect to the opening of a container, comprising a guide member, means whereby said guide member is positioned between the inner surface of said flange and the adjacent portion of the container, for controlling the relative movement between said closure and container, and automatic conveying mechanism for successively supplying said closures in proper position with respect to said guide member.
- 40 28. A device for placing a peripherally-flanged closure in closing position with respect to the opening of a container comprising a guide member, means whereby said guide member is positioned between the inner surface of the flange of the closure and the portion of the container adjacent the opening, for controlling the relative movement between said closure and opening, and automatic conveying means for successively supplying containers in proper position with respect to said guide member.
- 45 29. A device for placing a peripherally-flanged closure in closing position with respect to the opening of a container, comprising a guide member, means whereby said guide member is positioned between the inner surface of the flange of the closure and the portion of the container adjacent the opening, for controlling the relative movement between said closure and opening, and automatic conveying means for successively supplying containers in proper position with respect to said guide member.
- 50 30. A machine for placing peripherally-flanged caps in closing position with their flanges surrounding the tubular portions of containers, comprising a conveyor for the containers, a set of guide members traveling along with the containers of the conveyor, to be positioned between the flanges of the caps and said tubular portions, and means for withdrawing said members from between said flanges and said tubular portions.
- 55 31. A machine for placing peripherally-flanged caps in closing position with flanges surrounding the tubular portions of containers, comprising a conveyor for the containers, and a set of guide members traveling along with the containers on the conveyor, means whereby said guide members are positioned between the flanges of the caps and said tubular portions, and means for moving said members in their travel from a position in which they extend beyond the end of said tubular portion to a position in which they do not extend beyond the end of said tubular portion.

32. A device for placing a peripherally flanged closure in closing position with respect to the opening of a container, comprising a conveyor for carrying a container in a direction substantially transverse to the axes of the containers, and a guide member to be positioned between the surface of the flange of the closure and a portion of the container, and movable relative to said container and longitudinally of the axis thereof.

33. A machine for placing peripherally flanged caps in closing position with their flanges surrounding the tubular portions of containers comprising a conveyor for carrying the containers one after another in a direction transverse to the axes of the containers, and a plurality of sets of guide fingers, one set for each container, for traveling along with said containers, to be positioned between the flanges of the caps and the sides of the containers, and means for withdrawing said fingers from between said flanges and the sides of said containers to leave the caps in position on said containers.

34. A machine for placing peripherally flanged caps in closing position with respect to the openings of containers, comprising means for carrying the containers, one after another, in a direction transverse to the axes of the containers, a plurality of sets of guide fingers, one set for each container, for traveling along with said containers, means for supplying caps to said sets of fingers as they travel, means whereby the fingers of the sets are positioned between the flange of the caps and the sides of the containers, and means whereby said sets of fingers are withdrawn from between said flanges and sides of said containers to leave the caps in position on said containers.

35. A device for placing peripherally flanged closures in closing position with respect to the openings of containers, comprising guiding means adapted to extend between said containers and the closure flanges for positioning said closures correctly with respect to said openings as said closures and said containers are moved relatively toward each other and longitudinally of the axis of said container, and means for thereafter removing said guiding means in a direction transverse to the axis of said container.

36. A device for placing peripherally flanged closures in closing position with respect to the openings of containers comprising a guide member adapted to be positioned between the surface of the flange of the closure and a portion of the container and to be moved longitudinally relatively to said container and means for thereafter moving said guide member transversely of the axis of, and away from, said container.

37. A device for placing peripherally flanged closures in closing position with re-

spect to the openings of containers comprising guide fingers adapted to be positioned between the flanges of said closure member and a portion of said container, means for withdrawing said fingers from between said closure and said container portion in a direction longitudinal of the axis of said container, and means for thereafter moving said fingers transversely to the axis of, and away from, said container.

38. In a device for placing peripherally flanged closures in closing position with respect to the openings of containers comprising guide fingers adapted to be positioned between the flange of said closure member and a portion of said container, means whereby said closure may be initially positioned on said fingers, means for initially relatively moving said closure and said container in a direction longitudinal of the axis of said container whereby said fingers are disposed between said closure and said container to correctly position the former on the latter, means operating, after said correct positioning, to move said fingers longitudinally of the axis of said container and thereby withdraw the same from between said closure and container, and means for thereafter moving said fingers transversely to the axis of, and away from, said container.

39. In a device for placing peripherally flanged closures in closing position with respect to the openings of containers, a conveyor for said containers, divisible guide members adapted to be positioned between the flanges of said closures and containers, means for causing said members, as a whole, to travel along with the containers while they are effecting the proper positioning of the closures on the containers and for separating said members into their component parts and carrying said parts along separate paths at other times.

40. In a device for placing peripherally flanged closures in closing position with respect to the openings of containers, conveying mechanisms having orbital paths of movement which are substantially coincident during one portion of their travel, and component parts of guide members carried by said mechanisms, said parts being brought together to form a complete guide member where the mechanism paths substantially coincide, said member being positioned, during said time, between the flange of the closure and the container to properly seat the former and said guide members being again separated into their component parts as said conveyor mechanism paths diverge whereby said members are moved laterally away from said containers.

41. In a device for placing peripherally flanged closures in closing position with respect to the openings of containers, convey-

ing mechanisms having orbital paths of movement which are substantially coincident during one portion of their travel, guide members comprising a plurality of 5 fingers adapted to be disposed between the closures and the containers to properly seat the former on the latter, one half of the fingers of each member being mounted on one conveying mechanism and the other half of 10 said fingers being mounted on the other conveying mechanism and means for causing said mechanisms to so travel that the fingers are brought together to form a complete 15 guide member in the zone where the closures are placed on the containers, means for moving the complete guide members longitudinally of the containers to properly seat said closures, and means for thereafter separating the members into their component 20 parts and moving said parts of said members transversely away from the containers.

42. A device for placing peripherally flanged closures in closing position with respect to the openings of containers, chain conveyors having their paths of travel substantially coincident during one portion of their travel, guide members comprising a plurality of fingers adapted to be disposed 25 between the closures and the containers, said guide member being divisible and said fingers being mounted on the component parts of said members, means for mounting said parts on said chains so that, when they are brought together, they form complete members in the zone where the conveyor paths coincide, means for causing said chains to travel obliquely to the path of travel of said containers in said zone whereby the members as a whole move longitudinally of the containers to withdraw the fingers from between the closures and the containers and thereby properly seat the former on the latter, and means for thereafter separating 30 said members into their component parts and moving said parts transversely of, and away from, said containers.

43. A machine for placing peripherally flanged caps in closing position with their flanges surrounding the tubular portions of containers comprising a conveyor for the containers, a set of yielding guide fingers traveling along with the containers on the conveyor, means whereby said fingers are positioned between the flanges of the cap and said tubular portions, means whereby said containers and fingers travel in substantially straight lines oblique to each other during a portion of said travel to cause said fingers to move from a position in which they extend beyond the ends of said tubular portions, to a position in which they do not extend beyond said ends, and means for thereafter moving said fingers transversely 55 away from the capped container.

44. A machine for operating on containers comprising a conveyor, a plurality of holders carried by said conveyor for said containers, a guide chute along which said containers may be supplied to said holders, means governed by the correct positioning of a holder, with respect to said chute, for releasing a container therefrom, and means governed by the presence of a container on said holder for nullifying the releasing means and preventing the supply of a container to said holder upon which a container has been accidentally retained. 70

45. A machine for operating on containers comprising a conveyor, a plurality of 80 holders carried by said conveyor for said containers, a guide chute along which said containers may be supplied to said holders, means governed by the correct positioning to said holders, with respect to said chute, for 85 releasing the first container therefrom and for holding the second container against movement, and means governed by the accidental presence of a container on the next succeeding holder to prevent the delivery 90 of said second container into position whereby it will be fed to said last-named holder when the latter actuates said first named means.

46. A machine for operating on containers comprising a conveyor, a plurality of 95 holders carried by said conveyor for said containers, a guide chute along which said containers may be supplied to said holders, means governed by the correct positioning 100 of a holder, as well as by the absence of a container therefrom, for delivering a container from said chute to a properly positioned holder and for preventing such delivery when the holder so positioned is already occupied by a container. 105

47. A machine for affixing peripherally flanged closures to the openings of containers, comprising a conveyor for the containers, a guide member for traveling along with the containers, and means for controlling the movement of the guide members to position the latter between the flanges of the closures and the adjacent portions of the containers and control the relative movement between 110 the closures and the containers.

48. A machine for affixing peripherally flanged closures to the openings of containers, comprising a conveyor for the containers, a plurality of guide fingers for traveling 115 along with the containers, and means whereby said guide fingers are positioned between the flanges of the closures and adjacent portions of the containers, for controlling the relative movement between the closures and 120 containers.

49. In a device for placing peripherally flanged closures in closing position with respect to the openings of containers, chain conveyors having orbital paths of travel 130

- which are substantially coincident during one portion of their travel, a series of divisible guide members comprising a plurality of segmental supporting members, fingers 5 mounted on said segmental supporting members, one half of said fingers of each member being carried by one chain and one half by the other chain, means for mounting substantially one quarter of said fingers on one link of said chains and another quarter of said fingers on another link of the same chain whereby said quarter segments are brought together to form one half of a complete member which, with the corresponding 10 half member formed by the segments carried by the other chain, forms a complete operative member in the zone where the conveyor paths are substantially coincident, means for causing said chains to travel obliquely 15 to the path of travel of said containers in said zone whereby the members as a whole move longitudinally of the containers to withdraw the fingers from between the closures and the containers and thereby 20 properly seat the former on the latter, and means for thereafter separating said members into their component parts and moving said parts transversely of, and away from, said containers, said segments being so 25 mounted on said links that the segments carried by one chain are swung apart when rounding a corner and swung together whereby said quarter segments comprise substantially a half circumference when said 30 chains straighten out.
50. In a device for placing peripherally flanged closures in closing position with respect to the openings of containers, chain conveyors having orbital paths of travel 40 which are substantially coincident during one portion of their travel, guide members comprising a plurality of fingers adapted to be disposed between the closures and the containers, said guide members being divisible 45 and said fingers being mounted on the component parts of said members, means for mounting two of the component parts of one member on one chain and two of said parts of the same member on the other chain, 50 whereby a complete operative member is formed where said chain paths are substantially coincident, said parts on each chain being so arranged that they swing apart, when said chains diverge, to carry said 55 fingers away from the containers.
51. In a device for placing peripherally flanged closures in closing position with respect to the openings of containers, chain conveyors having orbital paths of travel 60 which are substantially coincident during one portion of their travel, sets of divisible guide members carried by said chains, said members comprising four segments; fingers mounted on said segments, two segments of 65 each set being mounted on one chain and the other two segments of that set being mounted on the other chain, means for so attaching the two segments on each chain thereto that, when the chains are straightened out, said segments form a half circle, 70 but, when said chains round a corner, said segments are swung angularly apart, means for driving said chains to bring said segments of each set together to form complete operative guide members where the conveyor 75 paths substantially coincide, means for causing said chains to travel obliquely to the path of travel of said containers in said zone whereby the members as a whole move longitudinally of the containers to withdraw the 80 fingers from between the closures and the containers and thereby properly seat the former on the latter, and means for thereafter separating said members in half, then swinging the quarter segments comprising 85 each half member apart, and thereby moving said fingers transversely of, and away from, said containers.
52. In a device for placing peripherally flanged closures or caps in closing position 90 with respect to the openings of containers, a divisible guide member comprising component parts having fingers mounted thereupon, said parts being brought together to assist in positioning said closures and being 95 movable apart to permit the discharge of a cap container, and the fingers moving between the flange of the closure and the container while assisting in said closing operation.
53. In a device for placing peripherally flanged closures or caps in closing position with respect to the openings of containers, a divisible guide member comprising component parts having fingers mounted thereupon, means for bringing said component parts together to form a complete guide member, means for placing a closure in operative relation with said fingers, and means for forcing the cap upon the container, the 100 fingers being between the cap flange and the container during the latter operation and being thereafter withdrawn from therebetween, said guide member being thereafter divisible into its component parts to release 110 the capped container.
54. In a device for placing peripherally flanged closures or caps in closing position with respect to the openings of containers, a divisible guide member comprising component parts having fingers mounted thereupon, means for bringing said component parts together to form a complete guide member, means for placing a closure in operative relation with said fingers, and means for forcing the cap upon the container, the 115 fingers being between the cap flange and the container during the latter operation and being thereafter withdrawn from therebetween, and means for thereafter dividing 120 the capped container.
60. In a device for placing peripherally flanged closures in closing position with respect to the openings of containers, chain conveyors having orbital paths of travel 125 which are substantially coincident during one portion of their travel, sets of divisible guide members carried by said chains, said members comprising four segments; fingers mounted on said segments, two segments of 65 each set being mounted on one chain and

said member into its component parts and moving the fingers relatively transversely of said capped container.

55. In a device for placing peripherally flanged closure or cap in closing position with respect to the openings of containers, a divisible guide member comprising component parts having fingers mounted thereupon, means for bringing said parts together and for moving them apart, means for placing a cap in operative relation to the fingers when the parts are together,

means for relatively moving said cap and container to place said cap on said container, the fingers during the latter operation passing between the cap flange and the container to assist in positioning said cap, and means for dividing said guide member into its component parts after the container is capped. 15

20 In witness whereof, I have hereunto subscribed my name.

JOHN L. FERGUSON.
